DESIGN FOR A COMBINATION LIP ROUGE HOLDER AND APPLICATOR

Rosalia Zumpano Sarff, New York, N. Y.

Application March 16, 1945, Serial No. 118,520

Term of patent 3½ years

(Cl. D86—10)

To all whom it may concern:

Be it known that I, Rosalia Zumpano Sarff, a citizen of the United States of America, residing in New York city, county of New York, and State of New York, have invented a new, original, and ornamental Design for a Combination Lip Rouge Holder and Applicator, of which the following is a specification, reference being had to the accompanying drawing, forming part thereof.

Fig. 1 is a front perspective view of a combination lip rouge holder and applicator showing my new design in closed position.

Fig. 2 is a front perspective view of the combination lip rouge holder and applicator as shown in Fig. 1, with the upper portion of the holder in open position and removed.

Fig. 3 is a rear perspective view of the combination lip rouge holder and applicator with the bottom portion removed.

Fig. 4 illustrates the bottom portion of the holder with the brush extending.

I claim:

The ornamental design for a combination lip rouge holder and applicator, substantially as shown.

ROSLIA ZUMPANO SARFF.
